By Watson E. Coleman, Attorney,

UNITED STATES PATENT OFFICE.

LEONARD P. WETZEL AND ARTHUR F. SELIGMAN, OF TROY, ILLINOIS.

INDEX LEDGER OR BALANCE SHEETS.

Application filed February 20, 1922. Serial No. 537,933.

To all whom it may concern:

Be it known that we, LEONARD P. WETZEL and ARTHUR F. SELIGMAN, citizens of the United States, residing at Troy, in the county of Madison and State of Illinois, have invented certain new and useful Improvements in Index Ledger or Balance Sheets, of which the following is a specification, reference being had to the accompanying drawings.

This invention relates to sheets designed to be used with bookkeeping or like machines, and particularly to sheets having an index portion or tab projecting from one side.

The general object of this invention is to provide a ledger sheet or balance sheet so constructed as to provide a tab, as it may be called, of greater or less length projecting from one side of the sheet and upon which the name of an account may be written, these sheets being arranged in series and the sheets of a series having the tabs so formed with relation to each other that when the series are all together, the names of the various accounts will be displayed.

A further object is to so form the sheet that the index tab will not tend to catch when the sheet is inserted between the rollers of a bookkeeping machine and thereby cause injury to the sheet itself or any buckling of the sheet, particularly when the sheets are reversed.

Other objects will appear in the course of the following description.

Our invention is illustrated in the accompanying drawings, wherein:—

The figure is a perspective view of a plurality of ledger or balance sheets designed in accordance with our invention, certain of the sheets being offset with relation to the main sheets.

Referring to this drawing, it will be seen that we have illustrated a series of index sheets running from one to 20, and certain extra sheets hereinafter specifically referred to. Normally there will be about twenty sheets in a series, though more or less sheets may be used. Each sheet 10 is preferably square in form and has its lower corners rounded or beveled, as at 11, the upper corners being also rounded or preferably beveled. To the right of each sheet and extending to the upper corner of the sheet is an extension of the sheet forming what we will call a tab and designated 12. This tab

on its lower margin is adapted to receive the name of the account, as at 13, and also a number 14, the numbers running consecutively through each series of sheets. The lower edge of this tab 12 is inclined, as at 15, and this inclination of this lower edge is a very important and necessary feature of the invention. It will be seen that the tab has a width such that the lower edge is long enough to receive the name of the account and, of course, this length is increased slightly by the inclination of this lower edge. The lower portion of each sheet is cut away below the tab and each succeeding sheet has its tab cut $\frac{1}{8}$ " shorter than the preceding sheet.

As before stated, there are approximately twenty sheets in a series, this being the greatest number possible with sheets of standard size, and the sheets are numbered from one to twenty, thus facilitating the replacement of the sheet. Of course, the usual alphabetical index tabs are to be used between the series of sheets and it can be readily seen that any certain account can be located instantly by glancing down the series of sheets. The lower portion of the sheet may be left plain or may be perforated, punched or notched, as desired, to fit any binder or holder, and we have indicated a certain form of notches which are designated 16. The sheets may be ruled in any manner desired and may be, of course, any width and length to fit any particular style of accounting and may be adapted, as before remarked, to fit any style of binder or holder. These sheets are particularly designed for use as "ledger" sheets or "statement" sheets used principally by banks.

As before remarked, the diagonal cut or diagonal edge at the lower end of the tab 12 is absolutely necessary in using the ledger sheet having an index tab with a bookkeeping machine, as where the tab 12 terminates at its lower edge in a margin extending at right angles to the vertical axis of the sheet this lower edge is very liable to catch in the rollers of the bookkeeping machine and tear or cause the sheet to buckle up. With the square-cut tab, the sheets are particularly liable to buckle up when reversed. Thus there will be a buckling of the sheet having a square-cut tab when the same is inserted in the bookkeeping machine, the sheet turned too far, and it is desired to turn it back. With our construction, the di-

agonal margin of the tab enters gradually between the rollers so that the tab is guided into the space between the rollers gradually instead of the right-angular lower edge of 5 the tab coming in contact along its whole edge with the rollers.

It will be noted from the figure that the sheets may be adapted to take care of more than one account of the same name when 10 the series of twenty sheets is already filled. In other words, there are two sheets numbered 12, two sheets numbered 11, two sheets numbered 10, etc., these second sheets 10, 11 and 12 lying normally beneath the outer sheets 10, 11 and 12 and the bookkeeper seeing the name "C. Anderson" on the main sheet but not the name "A. B. Anderson" or "O. A. Anderson," will simply lift up 15 the sheets above the name "Anderson" and 20 between the 12th sheet and the 13th sheet he will see the duplicate sheets 10, 11 and 12 having the other "Anderson" names thereon. This construction makes it extremely easy to find the proper account at 25 any time and even if the tabs are bent at an angle to the body of the sheet, they will readily pass between the rollers of the book-

keeping machine if the lower edge of the tab is inclined, whereas if the lower edge is square the tab is very liable to be torn off 30 or a tear started that will render the sheet useless.

Of course, we do not wish to be limited to any particular character of printing on the sheet, to any particular kind of notches, 35 etc. It is obvious that these may be varied in many ways without departing from the spirit of the invention.

We claim:

A series of balance or ledger sheets for 40 use with bookkeeping machines, each sheet having a relatively wide laterally projecting index tab, the lower edge of each tab being sharply inclined laterally and toward the top of the sheet, the tab of any one sheet 45 being longer than the tab of the next preceding sheet and underlying the tab of such preceding sheet throughout the length thereof, the upper edge of the tab being coincident with the upper edge of the sheet. 50

In testimony whereof we hereunto affix our signatures.

LEONARD P. WETZEL.
ARTHUR F. SELIGMAN.
